KANGAROO TOY

Stanley A. Duvall, Chicago, Ill.

Application March 8, 1945, Serial No. 581,599

11 Claims. (Cl. 46—123)

1

My invention relates to an improvement in toys and has for one purpose to provide a toy which combines motion and sound.

Another purpose is to provide a toy which simulates a mother kangaroo and its young.

Another purpose is to provide a toy which simulates the movement of a young kangaroo into and out of its mother's pouch.

Other purposes will appear from time to time throughout the specification and claims.

I illustrate the invention more or less diagrammatically in the accompanying drawings, wherein

Figure 1 is a side elevation with parts broken away and parts in vertical section;

Figure 2 is a plan view;

Figure 3 is a section similar to Figure 1 with the parts in a different position;

Figure 4 is a section on an enlarged scale on the line 4—4 of Figure 1;

Figure 5 is a side elevation of a variant form of the device, with parts broken away and parts in section; and

Figure 6 is a somewhat similar view of the parts in a different position.

Like parts are indicated by like characters throughout the specification and drawings.

Referring first to the form of Figures 1 to 4, I illustrate a toy which may be drawn by a child along a floor or pavement and which in response to its forward movement, causes motion of the moving parts of the toy, and may also cause a sound.

I generally indicates the supporting floor or surface. The toy includes a forward axle 2, having wheels 3 at opposite ends thereof and a rear axle 4 with wheels 5 fixed against rotation in relation thereto. The axle 4 has an eccentric or crank portion 6. Supported upon the wheels and axles is a carriage which includes the side members 7 and 8, the top member 9 and the bottom member 10. The parts may be secured together by any suitable securing screws 11. The forward axle 2 may be mounted upon any suitable front end member 12 secured in relation to the forward ends of the side members 7 and 8 and underlying the forward edge of the top member 9. 13 is a fixed post or guide extending upwardly from the top member 9. 14 is any suitable handle pivoted at the forward end of the toy as at 15 and provided with a hand engaging end portion 16.

Mounted for vertical reciprocating movement on the fixed square post 13 is a device shaped generally like the body of a kangaroo. This body

2

may be formed of two side portions 17 which are connected at their upper ends by an intermediate block or portion 18. This upper block, as will be clear in Figures 1 and 3 is shaped like the head of a kangaroo and may have inset eyes 19 of any suitable material.

The two side portions 17 are located at opposite sides of the fixed square post 13 and have connecting portions which surround it front and rear as at 20, 21. Secured to the forward lower part of the kangaroo body members 17, 17 are upper leg portions 22, 22 to which are pivoted as upon the pin 23, lower leg or foot portions 24, 24. When the parts are in the position of Figure 1, these foot portions 24 are generally horizontal and rest forwardly upon the top member 9 of the carriage. Pivoted to the rear of the body portion as at 25 is the kangaroo tail 26 which may engage the upper surface of the top member 9.

Within the space between the side body portions 17 and a back portion 27 is pivoted as at 28 an actuating lever 29, the upper end of which engages a controlling member 30, pivoted by means of the pin 31 to the body of the kangaroo. The members 30 and 31 are held against relative movement for example by the screw 32. The pin 31 has externally extending ends to which are secured the arms or forelegs 33, 33 of the kangaroo. Whereas the back of the kangaroo body is closed by the member 27, there is a gap in the forward part of the body as at 34. This permits the periodic escape of the head 35 of a baby kangaroo. This head is pivoted as at 36 to the upper end of the fixed post 13. When

the parts are in the lower position of Figure 1, the baby's head projects outwardly through the gap 34. But when the kangaroo body is raised as in Figure 3, the forward portion 37 of the kangaroo body engages the baby's head and moves it into withdrawn position in which it is shown in Figure 3.

In order to raise and lower the kangaroo body assembly on the fixed guiding post 13, I provide an actuating lever 40 which is pivoted as at 41 to an intermediate vertical support 42 which extends between the upper and lower carriage portions 9 and 10. It will be seen that the lower portion 10 terminates, as at 43, short of the rear end member 44 of the carriage, thus giving the lever 40 room to move. The upper surface of the rear end of the lever 40 is engaged by the eccentric portion 6 of the rear axle 4. Thus at each rotation of the axle 4 in response to the engagement of the wheels 5 with the ground, the lever 40 is oscillated about its pivot 41. It will be un-

55

derstood that the wheels 5 are locked against movement in relation to the axle 4. The result of the oscillation of the rear end of the lever 40 is to impart to the forward end a similar oscillation which is employed to raise and lower the kangaroo body. For example, I pivot a plurality of pins 46 to the forward end of the lever 40 as at 47. These pins 46 extend upwardly through the top member 9 of the carriage and engage the bottom of the kangaroo body. When the forward end of the lever 40 is in its lower position, the kangaroo rests by gravity in the position in which it is shown in Figure 1 with the tail 26 elevated, the forelegs 33 down and with the infant kangaroo's head 35 projecting outwardly through the gap 34 in the upper forward portion of the kangaroo body. The legs or feet 24 are generally horizontal. The result of raising the kangaroo body, by the oscillation of the lever 40, is shown in Figure 3. The front lower portion 37 of the kangaroo body pivots the infant kangaroo's head 35 to the withdrawn position of Figure 3. The legs or feet 24 are tilted. The tail 26 which is of substantial mass continues to rest on the upper surface of the member 9 but engages the lever 29 to raise the forelegs 33 of the kangaroo. As the carriage is drawn along the floor or pavement, the above described movement takes place in rapid succession, the infant kangaroo sticking its head out and withdrawing it at subsequent intervals as the carriage moves.

At the same time I may employ a sounding member such as the bellows 50, so that a sound will be made at each rotation of the rear axle 4. As an example I illustrate a top control plate 51 for the bellows 50 secured by screws 52 to the end of the lever 40. The lower end of the bellows may be secured to any suitable abutment 53 on the bottom member 10 of the carriage aligned with the air inlet and outlet aperture 54 which causes any suitable reed 55 to sound.

Referring to the form of Figures 5 and 6, I illustrate a cylindrical sleeve 60 having a top plate 61, and a lower end 62 apertured as at 63 to permit the passage of an actuating plunger 64 having an exterior actuating handle 65 and an inner head or guide 66. Compressed between the guide 66 and the end portion 62 of the sleeve 60, is a coil spring 67. The upper end of the sleeve 60 is closed by a closure plate 68 through which may pass actuating pins 69 mounted on the guide 66. A fixed guide 70 is mounted on the plate 68. Reciprocable on the guide 70 is a kangaroo body similar to the one shown in Figures 1 to 4 and generally indicated as 75, with the pivoted kangaroo tail 76, pivoted kangaroo feet 77, pivoted forefeet 78 and internal actuating lever 79. The baby kangaroo 80 is pivoted as at 81 to the upper end of the guide 70. 82 is any suitable sounding device adapted to be compressed between the lever 79 and the opposed back portion of the kangaroo body 75.

It will be realized that whereas I have shown and described an operative device, still many changes might be made without departing materially from the spirit of my invention. I wish, therefore that my showing be taken as in a broad sense diagrammatic and illustrative.

The use and operation of my invention are as follows:

In both forms of the device, I illustrate a kangaroo body within which is movably mounted the head portion of the baby kangaroo. The baby portion and the body portion are relatively movable. At one position, the head portion 80 of the

baby kangaroo extends outwardly through a front aperture in the body of the mother. The parts are shown in this position in Figures 1 and 6. In another position of the parts, the baby kangaroo's head is withdrawn as in Figures 3 and 5. In both forms, I employ a sounding means which is effective to cause a sound at the time that the head of the baby kangaroo projects. Note for example that the bellows 82 is compressed when the parts are in the position of Figure 6. Similarly the corresponding bellows is compressed when the parts are in the position of Figure 1 with the head of the baby kangaroo projecting.

As a matter of convenience in operation the form of Figures 1 to 4 is provided with a supporting and operating carriage, the kangaroo body being moved in response to movement of the carriage. The same result is obtained by hand in the form of Figures 5 and 6.

I claim:

1. In a toy, a platform, a body resembling a kangaroo and having a forward aperture, means for imparting relative movement of the body and the platform, an element resembling the upper portion of a baby kangaroo movably mounted within said body and means for imparting relative movement to the body and the element and for thereby simulating the movement of the head of a baby kangaroo out of and back into the pouch of a mother kangaroo.

2. In a toy, a platform, a body resembling a kangaroo and having a forward aperture, means for imparting relative movement to the body and the platform, an element resembling the upper portion of a baby kangaroo movably mounted within said body and means for imparting relative movement to the body and the element and for thereby simulating the movement of the head of a baby kangaroo out of and back into the pouch of a mother kangaroo, including a carriage, a wheeled axle on said carriage, and a connection extending from said wheeled axle to one of said members.

3. In a toy, a carriage, a guide on said carriage, a kangaroo body mounted on said guide for reciprocatory movement, an element representing the upper portion of a baby kangaroo movably mounted on said guide, said kangaroo body having an aperture aligned with said element through which said element may project, and means responsive to the movement of the carriage for reciprocating said kangaroo body on said guide, said kangaroo body including a portion adapted to move said element into withdrawn position in response to movement of said kangaroo body on said guide.

4. In a toy, a guide, a kangaroo body mounted on said guide for reciprocatory movement, an element representing the upper portion of a baby kangaroo pivoted on said guide, said kangaroo body having an aperture aligned with said element, through which said element may project, said kangaroo body including a portion adapted to move said element into withdrawn position in response to movement of said kangaroo body on said guide.

5. In a toy, a guide, a kangaroo body mounted on said guide for reciprocatory movement, an element representing the upper portion of a baby kangaroo, movably mounted on said guide, said kangaroo body having an aperture aligned with said element, through which said element may project, said kangaroo body including a portion adapted to move said element into withdrawn

position in response to movement of said kangaroo body on said guide.

6. In a toy, a guide, a kangaroo body mounted on said guide for reciprocatory movement, an element representing the upper portion of a baby kangaroo, movably mounted on said guide, said kangaroo body having an aperture aligned with said element, through which said element may project, said kangaroo body including a portion adapted to move said element into withdrawn position in response to movement of said kangaroo body on said guide and means for causing a sound when said kangaroo body is moved.

7. In a toy, a guide, a kangaroo body mounted on said guide for reciprocatory movement, an element representing the upper portion of a baby kangaroo, movably mounted on said guide, said kangaroo body having an aperture aligned with said element, through which said element may project, said kangaroo body including a portion adapted to move said element into withdrawn position in response to movement of said kangaroo body on said guide and means for causing a sound when said element projects from said kangaroo body.

8. In a toy, a platform, a body resembling a kangaroo and having a forward aperture, means for imparting relative movement to the body and the platform, an element resembling the upper portion of a baby kangaroo movably mounted within said body and means for imparting relative movement to the body and the element and for thereby simulating the movement of the head of a baby kangaroo out of and back into the pouch of a mother kangaroo, and means for causing a sound when the baby kangaroo element projects from said body.

9. In a toy, a carriage, a guide on said carriage, a kangaroo body mounted on said guide for reciprocatory movement, an element representing the upper portion of a baby kangaroo movably mounted on said guide, said kangaroo body having an aperture aligned with said element through which said element may project, and means responsive to the movement of the carriage for reciprocating said kangaroo body on said guide, said kangaroo body including a portion adapted to move said element into withdrawn position in response to movement of said kangaroo body on said guide and means for causing a sound when said element projects from said kangaroo body.

10. In a toy, a carriage, a guide on said carriage, a kangaroo body mounted on said guide

for reciprocatory movement, an element representing the upper portion of a baby kangaroo, movably mounted on said guide, said kangaroo body having an aperture aligned with said element through which said element may project and means responsive to the movement of the carriage for reciprocating said kangaroo body on said guide, said kangaroo body including a portion adapted to move said element into withdrawn position in response to movement of said kangaroo body on said guide, said reciprocating means including an axle on said carriage, said axle having an eccentric portion, a lever pivoted on said carriage, one end of said lever being

10 actuatingly connected to the eccentric portion of said lever, and an actuating connection between the opposite end of said lever and said kangaroo body.

11. In a toy, a carriage, a guide on said carriage, a kangaroo body mounted on said guide for reciprocatory movement, an element representing the upper portion of a baby kangaroo, movably mounted on said guide, said kangaroo body having an aperture aligned with said element through which said element may project and means responsive to the movement of the carriage for reciprocating said kangaroo body on said guide, said kangaroo body including a portion adapted to move said element into withdrawn position in response to movement of said kangaroo body on said guide, said reciprocating means including an axle on said carriage, said axle having an eccentric portion, a lever pivoted on said carriage, one end of said lever being actuatingly connected to the eccentric portion of said lever, and an actuating connection between the opposite end of said lever and said kangaroo body and sound creating means associated with said lever.
